APPARATUS FOR REGISTERING PRINTING ROLLERS, ESPECIALLY FOR COLOR PRINTING

Albert Navarre, Paris, France

Application March 17, 1948, Serial No. 15,316
In France June 20, 1947

5 Claims. (Cl. 33—184.5)

1

This invention relates to the registering of multiple printing rollers for colour printing, map printing and the like.

In the preparation of multiple rollers for colour printing for example, exact registering of areas which are to bear the several colours is essential. The relative positions of all points common to any one colour must be the same on the several printing rollers.

The apparatus of this invention is designed to enable corresponding points on identically similar printing rollers to be successively registered.

According to the invention, an apparatus for registering corresponding points on identically similar printing rollers, in which the rollers are mounted coaxially for common rotation, comprises a sheet of clear glass mounted so that it can be laid tangent to the rollers in a generally horizontal position and having a fiduciary line scribed thereon parallel to the roller axis and coinciding when the glass sheet is in operative position with the line of contact with the rollers, transparencies so supported that they can be laid on the glass sheet (one over each roller) and be moved both or all together in the direction parallel to the roller axis, their axial spacing being adjustable without disturbing their parallelism, each transparency having scribed thereon a fiduciary line transverse to the roller axis and parallel to the other transverse fiduciary line or lines, and a light projector mounted above each transparency and throwing a substantially vertical beam, so that the beams cast sharp shadows of the several transverse fiduciary lines and of the parts of the axial fiduciary line crossing them and that the intersections of these shadows on the surfaces of the rollers define corresponding points in register with each other.

Preferably the axial fiduciary line is scribed on the underside of the glass sheet which makes contact with the rollers; and the transverse fiduciary lines on the undersides of the transparencies which make contact with the glass sheet. This minimizes parallax and refraction errors.

The projectors are preferably mounted on a member which is so supported as to be able to slide in the direction parallel to the roller axis, and the transparencies are adjustably mounted on the sliding member so as to enable their axial spacing to be adjusted without disturbing their parallelism; and the sliding member may conveniently slide on a movable frame supporting the glass sheet. This frame may be mounted to rock about an axis parallel to the roller axis and be suitably counter weighted.

10 The transparencies may take the form of set squares; and the spacing of their transverse fiduciary lines can be adjusted once for all for each operation and remain constant throughout the operation, during which the whole assembly of transverse fiduciary lines is displaced parallel to the roller axis, as required for registering corresponding points at various positions on the rollers.

15 The intersections of the projections on the surfaces of the several rollers of the axial fiduciary line scribed on the glass sheet and of the several parallel transverse fiduciary lines, being intersections of a substantially vertical plane, similarly situated with respect to the several rollers, with a common generator of the cylindrical surfaces of all the rollers, define points in register with each other on the surfaces of the several rollers; and by bringing corresponding points of the blocks, transfers, negative or plates formed on or applied to the surfaces of the several rollers into coincidence with the intersections accurate registering is achieved.

20 The invention further includes a particular method of using the above described apparatus for applying transfers in different colours or bearing other complementary impressions to the several printing rollers in correct register with one another (whereby the subsequent printing-off is facilitated).

25 For this purpose the apparatus further includes provision for relative movement of the glass sheet and rollers, in the direction of rotation of the rollers, enabling rolling contact to be established between the glass sheet and rollers; and the method of applying the transfers to the rollers comprises the steps of temporarily securing the transfers to the underside of the glass sheet in positions determined by registering corresponding points thereof by the intersections of the optical projections of the fiduciary lines, the glass-sheet being held out of contact with the rollers, and then bringing the glass sheet down onto the rollers and applying pressure while the glass sheet and rollers are in rolling contact, so as to roll the transfers off onto the rollers.

30 It will be understood that the apparatus and method of the present invention for registering corresponding points on two or more identically similar printing rollers may be applied not only to colour printing but other analogous types of printing, e. g. map printing, which call for accurate registering of superimposed impressions.

35 A specific example of the apparatus is described below with reference to the accompanying drawings, of which:

2

Figure 1 is a perspective view of the apparatus; Figure 2 is an explanatory perspective diagram. The apparatus as shown in the drawing (Figure 1) comprises two identically similar printing rollers 1, 2 mounted coaxially on a common shaft 3 whose ends 4, 5 are supported in pedestal bearings, as shown. The rollers are located on the shaft by means of four adjustable collars 6 and the shaft can be rotated by means of a hand wheel 7, the rim of which may bear graduations 8, rotatable against a fixed mark (not shown).

A flat sheet 12 of clear plate glass spanning both the rollers is supported at its ends in the side rails 10 of a U-shaped rocking frame mounted to rock on the cross bar 9 of a fixed bridge, the cross bar being parallel to the shaft 3 and the rocking frame being provided with a counterweight 11 for balancing the frame and the equipment supported by it including the glass sheet 12.

Spanning the side rails 10 of the rocking frame is a cross bar 14, which, too, is parallel to the axis of the roller shaft 3 and the axis 9 on which the rocking frame rocks. A tubular support 21 is mounted to slide lengthwise on the cross bar 14 and carries two transparent set squares 15, 16 which rest on the upper surface of the glass sheet 12 over one and the other of the rollers 1, 2. On the tubular member 21 are rigidly mounted standards carrying light projectors 19, 20 which throw substantially vertical beams down onto the set squares 15, 16, respectively.

On the underside of the glass sheet 12 is scribed a fiduciary line 13 which is accurately parallel to the axis of the roller shaft 3 and on the undersides of the set squares 15, 16 respectively are scribed fiduciary lines 17, 18 which cross the line 13 and are accurately parallel to one another. It is important that the mutual spacing of the lines 17, 18 register with that of the light projectors 19, 20. To enable the mutual spacing of the lines 17, 18 to be adjusted without disturbing their parallelism when the apparatus is set in use, the relative positions of the set squares 15, 16 lengthwise of the tubular member 21 may be adjustable. In the example shown, the set squares are mounted in a longitudinal slot of the tubular member 21; and one of both of the set squares may be adjustably movable along the slot. In this manner the lines 17 or 18 may be set in registration with the related light projector 19 or 20, in order that said associated light reflectors and lines define parallel planes P, preferably vertical ones.

The light projectors 19, 20 are so placed that their beams are directed onto the fiduciary lines 17, 18, respectively, where they cross the fiduciary line 13 so as to cast shadows of the crossing portions of these lines onto the surfaces of one and the other of the rollers 1 and 2. In this way the fiduciary lines are optically projected onto the surfaces of the rollers and the intersections of these projections define points on one and the other of the rollers which are accurately in register. The fiduciary line 13 is projected as a generator of the cylinder defined by the surfaces of the rollers 1 and 2 (see Figure 2); and the fiduciary line 17 (or 18) is projected as the intersection of a plane P containing the line 17 (or 18) and the light source 19 (or 20) (see Figure 2).

It will be evident that displacement along the cross bar 14 of the assembly comprising the tubular member 21, the set squares 15, 16 and the projectors 19, 20, will not affect the attitude of the planes P which remain parallel to their initial

planes; while the generator 13 (see Figure 2) remains stationary in space as long as the glass sheet 12 is not moved.

It should here be explained that the fiduciary line 13 is so located on the underside of the glass sheet 12 that when the latter is lowered into contact with the rollers, the line 13 coincides with the line of contact. By scribing the line 13 on the underside of the glass sheet 12 and by so locating it with respect to the rollers, its optical projection on the surfaces of the rollers is not affected by parallax or refraction; and since the lines 17, 18 are scribed on the undersides of the set squares, their optical projections on the rollers are affected by parallax and refraction to the least possible extent. Moreover, the parallax and refraction effects to which the projections of lines 17 and 18 are subject are constant, since the relative positions of the projectors 19, 20 and set squares 15, 16 are not affected by endwise displacement of the tubular member 21, so long as the mutual spacing of the set squares and their fiduciary lines 17, 18 is not disturbed.

Successive registering of corresponding points 25 on the surfaces of rollers 1 and 2 is achieved by rotating the shaft 3 and sliding the tubular member 21 to bring the intersection of the optical projections of fiduciary lines 13 and 17 into coincidence with a given point on the surface of 30 roller 1. The corresponding intersection of the optical projections of fiduciary lines 13 and 18 on the roller 2 will then define the position of the corresponding point on the surface of roller 2 enabling it to be correctly registered. The procedure is then repeated for another point on the 35 surface of roller 1, and so on.

In order to achieve high accuracy of registering, suitable optical devices could be provided for viewing the intersections of the projections of 40 the fiduciary lines. Similarly, the movement of the tubular member 21 along the cross bar 14 and the rotation of the shaft 3 could be regulated by means of micrometer devices.

For simultaneously registering three or more 45 printing rollers, the apparatus could be modified by making the shaft 3 long enough to accommodate the greater number of rollers and by providing the tubular member 21 with one or more additional set squares each bearing a transverse fiduciary line and an additional projector or projectors. Intermediate pedestal bearings for the shaft 3 could be provided, as required, to prevent the shaft from sagging owing to its great length.

What I claim is:

55 1. Apparatus for registering printing rollers, especially for colour printing, comprising in combination: a plurality of removable printing cylinders, each corresponding to a separate colour in the print to be obtained, respectively coaxially 60 arranged along a common axis; stop means for securing said cylinders against axial displacement; a support extending parallel to said common axis; a rocking frame pivotally mounted on said support; a glass sheet attached to said frame 65 adapted to rest on said cylinders; a fiduciary line on said glass sheet, parallel to said common axis; a plurality of transparent squares resting on said glass sheet equal in number to said cylinders, and rigidly spaced with respect to each other in an amount equal to the spacing between the related cylinders, respectively; a fiduciary line on each of said squares, said fiduciary lines being parallel to each other and out of parallelism with said first-mentioned line on said glass sheet; a sliding 70 support for said squares; guiding means for said 75 support for said squares; guiding means for said

sliding support, attached to said rocking frame and parallel to said common axis; a plurality of light projectors each associated with a related one of said squares; and supporting means for said light projectors attached to said sliding support.

2. Apparatus for registering printing rollers, especially for colour printing, comprising in combination: a plurality of removable printing cylinders, each corresponding to a different colour in the print to be obtained, and coaxially arranged along a common axis; stop means for securing said cylinders against axial displacement; a support extending parallel to said common axis; a rocking frame pivotally mounted on said support; a glass sheet attached to said frame adjacent said cylinders; a fiduciary line on said glass sheet parallel to said common axis; a plurality of transparent squares resting on said glass sheet, whose number is equal to that of said cylinders; a fiduciary line on each of said squares, said fiduciary lines being parallel to each other, respectively, and out of parallelism with said fiduciary line on said glass sheet; a sliding support on said frame; guiding means for said sliding support attached to said frame and parallel to said common axis; a plurality of light projectors whose number is equal to the number of said squares and of said cylinders; supporting means for said light projectors attached to said sliding support; and a longitudinal notch in said sliding support

receiving said squares whereby the positions thereof with respect to the related light projectors may be accurately determined.

3. An apparatus as set forth in claim 1, wherein said support parallel to said common axis is located substantially in the horizontal plane through the top line of said cylinders.

4. An apparatus as set forth in claim 1, wherein said first-mentioned fiduciary line is drawn on the under surface of said glass sheet, thereby lying in close contact with said cylinders when said glass sheet is in operative position, whereby any parallax error is minimized.

5. An apparatus as set forth in claim 1, wherein said fiduciary lines on said transparent squares are drawn on the under surface thereof in contact with said glass sheet, whereby any parallax error is minimized.

ALBERT NAVARRE.
